7 Claims. (Cl. 60—41)

1

It is known to evaporate the cooling water of water-cooled gas turbines and to use the steam which is thus generated for heating and power purposes.

If the heating is not done by means of an electrical resistance heater supplied with current from a generator driven by the turbine, un-cooled gas turbines necessitate the installation of a special heating boiler, for instance when the rooms which have to be heated are already provided with radiators for steam or hot-water heating, as is often the case in many railway carriages. When such a train is driven by a gas turbine locomotive then it is preferable that the heat carrier for heating the carriages, that is the steam or hot water, should be produced in the locomotive itself, at least part of the gases generated in the combustion chamber of the gas turbine being used for this purpose according to the present invention.

According to the invention a train heating plant for applying this method in practice consists of a heating surface for indirect heating which is arranged to be subjected to the influence of the gas stream.

Preferred embodiments of the invention will be described with reference to the accompanying drawing, in which:

Fig. 1 is a diagrammatic representation of one embodiment of the invention;

Figs. 2 and 3 are fragmentary diagrammatic views of other heat-exchange arrangements; and

Fig. 4 is a diagrammatic view of an embodiment of the invention in which the train heating system may be operated from an independent fuel supply when the combustion turbine plant of the locomotive is not in operation.

In the figures, 1 indicates the combustion chamber, 2 the gas turbine, 3 the compressor for the combustion air, 4 the preheater which is heated by the exhaust gases from the turbine, 5 a gear, 6 an electrical current generator, and 7 a heating boiler.

In Fig. 1 the heating boiler 7 is located separately from the gas turbine plant next to the combustion chamber 1 and connected to this latter by a pipe 9. Whilst the greater part of the combustion gases flow through conduit 10 to gas turbine 2, a small part of these gases can pass through pipe 9 to boiler 7 when valve 11 is open. In this boiler 7 the gases come into contact with the tube coil 12, also called heating surface, through which water circulates and when valve 14 is open these gases pass through pipe 13 to an intermediate stage of turbine 2 where the pres-

sure gradient corresponds approximately to that of the boiler, the residual pressure of the exhaust gases then doing useful work in the turbine. The efficiency of the heating plant is thus considerably higher than if the heating gases are allowed to escape to the atmosphere, in which case they must be so strongly throttled that the pressure in the boiler is just high enough to overcome its resistances. Valves 11 and 14 enable the supply and discharge of the hot gases to and from the heating boiler 7 to be regulated. These valves are controlled by an adjusting mechanism 15 whose spring-loaded piston, for instance in dependence on the steam pressure in pipe 16 acting through pipe 17, displaces these valves. Thus when the steam pressure decreases, the valves are opened until the desired steam pressure is reached. 18 is a feed-water tank from which boiler 7 is supplied by means of the electric feed-water pump 19 and pipe 20. When valves 11, 14 are opened 20 19 must be set into operation so that fresh feed water is always supplied to the boiler. Feed-water tank 18—on condition that steam is produced—is connected to the steam pipe 16 by means of pipe 21 and a non-return valve 22 in such a manner that in case there is a large rise in pressure in pipe 16, due to very little or no steam being taken from this pipe, steam can flow into the feed-water tank 18 where it can partly condense or discharge through escape valve 23 to the atmosphere. The supply of feed water to steam producer 7 is regulated by a throttle valve 25 so that when the steam pressure increases the supply of feed water decreases. The feed water is thus regulated in the same sense as the heating gases and by the same adjusting mechanism 15. By this means excessive steam production is prevented when requirements are small and on the other hand the steam pressure can automatically be kept approximately constant.

If the carriages are to be heated with hot water instead of steam, then adjusting mechanism 15 is actuated by a thermostat which is influenced by the hot water in such a manner that for instance the water delivered by the feed pump is passed to the underside of the piston of mechanism 15 and the pressure regulated so that with an increasing temperature the gas and feed-water supply to boiler 7 is throttled and when the upper limit for the water temperature is reached it is even completely shut off.

With the arrangements shown in Figs. 2 and 3 no special heating boiler is provided.

In the case of Fig. 2 the steam or hot water generator in the form of tubes 12 arranged

transversely to the gas stream are located in the gas flue between combustion chamber 1 and gas turbine 2, whilst in the case of Fig. 3 these tubes are wound round the combustion chamber. Regulation with a thermostat is very simple, a temperature drop being caused by the heat taken from the heating element which directly affects the regulation of the fuel in the combustion chamber, so that no special regulation for the heating is necessary.

If it is not desirable to have an auxiliary boiler in addition to the main boiler, but it is nevertheless desired that it should be possible to supply the heating plane (radiators) of a train for instance even when the gas turbine set is not running, then the arrangement shown in Fig. 4 can be used. Here the boiler 7 in addition to being heated with gas is also provided with an oil burning plant comprising an oil burner 8, a combustion air blower 24, and fuel tank 38 with fuel pump 39 and adjustable supply pipe 40.

With both methods of operation, that is heating with hot gases or oil, feed water is supplied from tank 18 by the electrically operated pump 19 over the supply regulating valves 42 or 41. Valve 41 together with gas valves 11, 14 is under the influence of adjusting mechanism 15, whilst valve 42 together with the regulating valve 43 in pipe 40 is actuated by adjusting mechanism 44. Control switch 45 enables the heating plant for oil or gas operation to be switched in as desired.

The conditions for both kinds of operation are as follows, if for instance it is assumed that heating steam is to be produced.

1. Operation with hot fresh gases from the combustion chamber: Control switch 45 is brought into position A where the underside of the piston of adjusting mechanism 15 is connected to pipe 17. If combustion chamber 1 is in operation and feed-water pump 19 is running, steam will be generated in coil 12. When the steam has reached the desired pressure which can be adjusted by means of the spring above the piston of adjusting mechanism 15, the gas flow is throttled by valves 11, 14 or even entirely stopped. The supply of feed water is throttled in a similar manner by the feed water valve 41 which is also under the influence of adjusting mechanism 15. As soon as the steam pressure in pipe 17 drops valves 11, 14 and 41 are opened again and steam production increased. During this method of operation adjusting mechanism 44 is not under pressure and valves 42 and 43 are therefore closed.

2. Operation with oil-burning plant: Combustion chamber 1 is not in operation. In this case control switch 45 is brought into position B whereby adjusting mechanism 44 with its spring-loaded piston and also adjusting mechanism 47 which opens valve 46 are connected to steam pipe 17, valve 46 serving to discharge the combustion gases to the atmosphere because the path to the turbine 2 is closed. Adjusting mechanism 15 is out of operation and valves 11, 14 and 41 are closed. On the other hand feed-water valve 42 and fuel valve 43 are open. Burner 8 is ignited in a known manner. The generation of steam is regulated by adjusting mechanism 44 in such a manner that when the steam pressure becomes excessive fuel valve 43 and feed-water valve 42 throttle the supply of oil and feed water respectively.

In all the arrangements which have been described the pressure is regulated automatically.

For the sake of simplicity all such known elements as safety and excess-pressure valves and

the like, which are not directly concerned with the invention, have been omitted from the drawings.

We claim:

5. 1. A heating system for a train driven by a locomotive of the combustion gas turbine type including a combustion chamber, a compressor for supplying compressed air to said combustion chamber, a turbine driving said compressor, and 10 a conduit connecting said combustion chamber to the inlet of said turbine to establish a stream of combustion gases therethrough; said heating system comprising a heat exchanger, a second conduit leading from said combustion chamber in parallel with said first conduit and opening into said heat exchanger, a pipe for exhausting from said heat exchanger the stream of combustion gases delivered thereto through said second conduit, means for passing a heat-carrying medium through said heat exchanger in heat exchange relation to the combustion gases flowing therethrough, and means including said pipe for introducing the combustion gases exhausted from said heat exchanger into the stream of combustion gases established by said first conduit, and means for merging said streams of combustion gases after the stream in said second conduit has transferred heat to the heat-carrying medium.

2. A heating system as recited in claim 1, wherein said turbine is a multistage turbine having an auxiliary inlet to an intermediate stage thereof, and said last-mentioned means connects said exhaust pipe to the auxiliary inlet of said turbine.

3. A heating system as recited in claim 1, in combination with means operative independently of said combustion chamber for establishing a flow of combustion gases through said second conduit, whereby said heat-carrying medium may be heated during periods when said combustion gas turbine is not operating.

4. A heating system for a train driven by a locomotive of the combustion gas turbine type including a combustion chamber, a compressor for supplying compressed air to said combustion chamber, a multistage turbine driving said compressor, said turbine having a main inlet and an auxiliary interstage inlet, and a conduit connecting said combustion chamber to said main inlet of the turbine; said heating system comprising a second conduit leading from said combustion chamber in parallel with said first conduit, passage means within said second conduit to be heated by combustion gases flowing therethrough, means for passing a heat-carrying medium through said passage means, a pipe connecting the outlet end of said second conduit to said auxiliary interstage inlet of said turbine, valve means adjustable to control the flow of combustion gases through said second conduit, and control means responsive to a condition of the heat-carrying medium discharged from said passage means for adjusting said valve means.

5. A heating system for a train driven by a locomotive of the combustion gas turbine type including a combustion chamber, a compressor for supplying compressed air to said combustion chamber, a multistage turbine driving said compressor, said turbine having a main inlet and an auxiliary interstage inlet, and a conduit connecting said combustion chamber to said main inlet of the turbine; said heating system comprising a second conduit leading from said combustion chamber in parallel with said first conduit, pas-

sage means within said second conduit to be heated by combustion gases flowing therethrough, a water storage tank, a pump for supplying water from said tank to said passage means for vaporization therein, a pipe connecting the outlet of said second conduit to said auxiliary interstage inlet of said turbine, and control means responsive to the steam pressure at the outlet of said passage means for adjusting the rate of water supply to said passage means and the flow of combustion gases through said conduit.

6. A heating system as recited in claim 5, in combination with auxiliary means operable independently of said combustion chamber for heating said second conduit; said auxiliary means including a burner nozzle at the inlet end of said second conduit, means for supplying fuel and air to said burner nozzle, and a valve-controlled vent outlet for the escape of combustion gases from said second conduit during operation of said auxiliary means.

7. A heating system as recited in claim 5, in combination with auxiliary means operable independently of said combustion chamber for heating said second conduit; said auxiliary means including a burner nozzle at the inlet end of said second conduit, means for supplying fuel and air to said burner nozzle, a valve-controlled vent outlet for the escape of combustion gases

from said second conduit during operation of said auxiliary means; a second control means responsive to said steam pressure for adjusting the rates at which fuel is supplied to said burner nozzle and water is supplied to said passage means, and means adjustable to energize said first control means during operation of said combustion chamber and alternatively to energize said second control means during operation of said auxiliary means.
